[57] CLAIM

The ornamental design for a utility wagon, as shown and described.

DESCRIPTION

FIG. 1 is a top perspective view of a utility wagon showing my new design;

FIG. 2 is a top plan view thereof;

FIG. 3 is a left side elevational view thereof, the right side elevational view being a mirror image of that shown;

FIG. 4 is a bottom plan view thereof;

FIG. 5 is a front elevational view thereof; and,

FIG. 6 is a rear elevational view thereof.
